UNITED STATES PATENT OFFICE.

THEODOSIUS A. WILLIAMS, OF PORTLAND, OREGON.

FLASH-LIGHT STAND.

1,403,725.

Specification of Letters Patent. Patented Jan. 17, 1922.

Application filed November 10, 1920. Serial No. 423,004.

To all whom it may concern:

Be it known that I, THEODOSIUS A. WILLIAMS, a subject of the King of England, residing at Portland, in the county of Multnomah and State of Oregon, have invented a new and useful Flash-Light Stand, of which the following is a specification.

My invention relates to improvements in flashlight stands in which the commercial variety of flashlights may be used stationarily to illuminate any desired point in the vicinity of the stand.

The objects of my invention are to produce a stand which can be manufactured cheaply, which possesses little bulk, which can be easily affixed to a flashlight and which permits the flashlight to throw its rays in any desired direction.

I attain these objects with the mechanism illustrated in the accompanying drawing, in which—

Fig. I is a front elevation of the stand with the flashlight in place.

Fig. II is a plan view of Fig. I.

Fig. III is a side elevation of Fig. I.

Fig. IV is a plan view of the stand alone. Similar numerals refer to similar parts throughout the several views.

On a circular base 1 having a downwardly rolled edge 2 are supported the two flexible pillars 3. Pivotaly mounted at the upper ends of the pillars are the curved leaf springs 4 which engage like the jaws of a vise the shaft of the flashlight 5 and enable the latter to turn between the pillars as around a horizontal axis. Immediately above the circular base the pillars join to a semi-circular funnel 6 whose bottom edge merges with the rolled edge of the base and thus, by avoiding sharply projecting edges, facilitates the withdrawing of the flashlight and stand from a coat pocket. Ordinarily the lower part of the flashlight will rest between the pillars and against the wall of the funnel, held in that position not only by the resiliency of the pillars and the curved leaf

springs, but also by a nose 7 which projects upward through a slot 8 in the circular base. This nose is formed by crimping one end of a flat spring 9 whose other end is riveted at 10 to the underside of the circular base. When stationary use of the flashlight is intended, said nose will yield very readily on pressure exerted against the flashlight in the direction of the arrow 11 in Fig. III. 55 The limit of the rotation of the flashlight is indicated by the dotted lines 12 in Fig. III. The numeral 13 indicates the customary flashlight switch.

Having thus described my invention, it 60 will be seen that my objects have been accomplished.

I claim:

1. A flashlight stand, comprising a circular base of larger diameter than the casing of a flashlight, a wall on top of said base around one-half thereof, said wall inclining gradually toward the flashlight casing and forming a cradle for the lower end of the flashlight, pillars extending upwardly 70 from the ends of the wall and parallel to each other, leaf springs bent to the curvature of the flashlight casing and pivotally mounted in the upper terminals of the pillars, and means to hold the lower end of a flashlight temporarily in said cradle, said means comprising a flat spring riveted to the circular base.

2. A flashlight stand, comprising a circular base having a downwardly projecting 80 rolled edge, flexible pillars firmly attached to the base, a flashlight mounted revolubly between the pillars, a slot in the base, a flat spring riveted with one end to the underside of the base, a nose crimped into the 85 free end of said spring, said nose projecting through the slot in the base and engaging a point at the circumferential edge at the bottom of the flashlight.

Signed by me at Portland this 5th day of 90 November, 1920.

THEODOSIUS A. WILLIAMS.
